FIG. 1 is a top view of a one-piece pool having slide showing my design;

FIG. 2 is a left side view of said one-piece pool having slide;

FIG. 3 is a front view of said one-piece pool having slide;

FIG. 4 is a rear view of said one-piece pool having slide;

FIG. 5 is a bottom view of said one-piece pool having slide; and

FIG. 6 is a sectional view taken substantially along the line 6—6 of FIG. 1.

Since the one-piece pool having slide is symmetrical, the right side view thereof is the same as the left side view.

I claim:

The ornamental design for a one-piece pool having slide, substantially as shown and described.
